UNITED STATES PATENT OFFICE.

JAMES THOMAS PARKER, OF BIRMINGHAM, ALABAMA.

AUGER-BIT.

1,111,318.

Specification of Letters Patent. Patented Sept. 22, 1914.

Application filed August 3, 1912. Serial No. 713,124.

To all whom it may concern:

Be it known that I, JAMES T. PARKER, a citizen of the United States, residing at Birmingham, in the county of Jefferson and State of Alabama, have invented a new and useful Auger-Bit, of which the following is a specification.

The present invention relates to certain improvements in expansible auger bits, the present invention being particularly an improvement over the auger bit disclosed in my former Patents Nos. 825,479 and 850,177 issued July 10, 1906 and April 16, 1907, respectively.

It is the object of the present invention to provide an expansible bit which is simple, durable, substantial, compact and inexpensive in construction, and one which shall be convenient, serviceable and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention has been illustrated in its preferred embodiment in the accompanying drawings, wherein—

Figure 1 is a front elevation of an auger bit embodying the present invention. Fig. 2 is a side elevation thereof. Fig. 3 is a sectional detail taken on the line 3—3 of Fig. 2. Fig. 4 is a longitudinal sectional view of the bit. Fig. 5 is a perspective view of a locking lever employed in carrying out the invention.

Referring specifically to the drawings, the numeral 6 designates the shank of the bit, which is provided at its outer or lower end with an enlarged semi-cylindrical head 7 terminating at its outer end in a cutting head 8 and a screw tip 9, as usual. The foregoing parts are customary in an expansible bit, and need no further description.

In carrying out the present invention, a transverse slideway is provided in the flat face of the head 7 adjacent the cutting head 8, the slideway comprising a transverse channel 10 and a T-groove 11 at the bottom

of the channel, the inner edge of the channel 10 being undercut as designated by the numeral 12. The head 7 is also provided with a narrow longitudinal groove 13 extending inwardly from the channel 10 and into the shank 6 for a short distance, the groove 13 being made deeper at an intermediate portion within the head 7, as designated by the numeral 14, and the bottom 65 of the inner end of the groove being curved to the surface of the shank. The sides of the grooves are straight and parallel. The edges of the shank 6 formed by the groove 13 are cut away as designated by the numeral 15 in order to provide depressions for the purpose hereinafter set forth. This groove 13 may be readily provided by means 70 of a milling machine, as well as the slideway, which methods are well known to the 75 mechanic.

The usual cutter 16 is slidable in the slideway, the cutter fitting in the channel 10 flush with the flat face of the head and having a T-tongue 17 engaging the T-groove 80 11 so as to permit the cutter to slide longitudinally within the slideway, but to be constrained against other movements. The inner or upper edge of the cutter 16 is beveled and toothed as designated by the numeral 85 18 and works under the cut-away portion of the channel 10. The slideway and cutter are preferably inclined slightly from the horizontal in order to facilitate the cutting action.

A locking lever 19 is coextensive with and fits snugly between the sides of the groove 15 and has an extension or lug 20 projecting from its intermediate portion into the deepened portion 14 of the groove, and a fulcrum pin 21 is passed through the head 7 and through the extension 20 of the lever in order to fulcrum the lever within the groove. The lever 19 fits within the flat face of the head 7 and is flush therewith and the lower 100 or outer end of the lever is beveled and toothed as designated by the numeral 22 in order to engage the beveled and toothed edge 18 of the cutter. The upper end of the lever within the shank is offset and diverges 105 outwardly so as to normally project slightly from the shank 6 as designated by the numeral 23.

In order to normally force the lever 19 into engagement with the cutter, a spring 24 110 is arranged between the inner end of the lever and the bottom of the groove 13, the

spring 24 being in the form of a leaf spring having one end engaged in a kerf 25 provided in the inner end of the extension 20 and lying against the lever with its free end 5 engaging the curved portion of the bottom of the groove 15. The kerf of the extension or lug is flush with the lever proper in order that the corner provided by the offset portion 23 of the lever will contact with the 10 intermediate portion of the leaf spring, thereby gaining considerable tension.

For convenience in setting the cutter, a scale of graduations 26 are provided on the outer face of the cutter along its inner end, 15 which cooperate with the pointer or guide mark 27 on the head 7.

From the foregoing, taken in connection with the drawings it will be apparent that ordinarily the spring 24 will swing the inner arm of the lever 19 outwardly so that the outer end of the lever engages the inner edge of the cutter in order to lock the cutter against transverse motion. By depressing the inner end of the lever 19, which is 20 rendered easy by the depressions 15, the lever may be swung out of engagement with the cutter so that the cutter may be adjusted transversely to the proper position. The cutter is thus capable of being set at 25 various positions for cutting various sized holes and as soon as the lever is released, the same will engage the cutter.

It will be observed, that the present bit is of very simple and compact construction, 30 which is highly desirable, and carries out the objects aimed at in a satisfactory manner.

Having thus described the invention, what is claimed as new is:

40 1. An auger embodying a shank having a semicylindrical head, the head having a transverse channel in its flat face and a long narrow groove extending from the channel into the shank, the sides of the groove being flat and parallel, and the inner end of the 45

bottom of the groove being curved to the surface of the shank, a cutter slideable in the channel, a lever coextensive with and fitting snugly between the sides of the groove, the lever having an intermediate lug, a pivot 50 pin passing through the head and said lug, the outer end of the lever being engageable with the cutter, the inner end of the lever being offset outwardly, the lug having an inner kerf flush with the lever, and a leaf 55 spring having one end fitting in the kerf with the other end engaging the curved portion of the groove.

2. A bit including a shank, a head, a cutter integral with the head, and a screw tip 60 extending from said cutter, there being a transverse guide groove in one face of the head and close to the cutter and a longitudinal groove in said face of the head and opening into the transverse groove, an adjustable cutter slidably mounted in the transverse groove and having a toothed upper edge, a lever fulcrumed in the longitudinal groove and having a toothed lower end, and a spring interposed between the 65 head and lever and seated in the longitudinal groove for holding the upper end of the lever normally projected beyond the shank and for holding the toothed end of the lever normally in engagement with the 70 toothed edge of the slideable cutter to hold said cutter against movement transversely of the plane of movement of the lever, the upper normally projecting end of the lever being depressible into the longitudinal 75 groove to disengage the toothed end of the lever from the slideable cutter.

In testimony that I claim the foregoing as my own, I have hereto affixed my signature in the presence of two witnesses.

JAMES TOHMAS PARKER.
